UNITED STATES PATENT OFFICE

OBED O. LEES AND THOMAS J. FINN, OF COLUMBUS, OHIO; SAID LEES ASSIGNOR TO SAID FINN; ELLA S. DAILEY, EXECUTRIX OF SAID THOMAS J. FINN, DECEASED

RAILROAD CROSSING GATE

Application filed July 14, 1930. Serial No. 467,915.

This invention appertains to new and useful improvements in railroad grade crossing gates, and more particularly to a gate of the motor operative type.

5 The principal object of the invention is to provide a railroad gate adapted to be actuated through the agency of a railroad block circuit.

Another object of the invention is to provide 10 a railroad gate which will permit vehicles trapped on the railroad tracks to pass therethru.

During the course of the following specification, other important objects and advantages 15 of the invention will readily become apparent to the reader.

In the drawings:—

Figure 1 represents a side elevational view 20 of the novel gate structure.

Fig. 2 represents a fragmentary top plan view of the gate structure.

Fig. 3 represents a horizontal sectional view through the gate structure, taken substantially on the line 3—3 of Fig. 4.

25 Fig. 4 represents a vertical sectional view through the mechanism for operating the gate.

Fig. 5 represents a side elevational view of the trackway for the structure shown in 30 Fig. 4.

Fig. 6 represents a fragmentary side elevational view of the governor.

Referring to the drawings wherein like 35 numerals designate like parts, it can be seen that numeral 5 represents a raised base structure of circular formation, upon which the track 6 is mounted. The track 6 is of annular formation, and has inclined portions thereon, leading upwardly to risers 7 which

40 serve as abutments for the casters 8 on the bottom of the platform 9. This platform 9 is located within the cylindrical housing 10, is suitably secured thereto and supports the motor 11. The armature shaft of the motor

45 11 is provided with a bevel gear 12 for mesh with the bevel gear 13 on the vertical shaft 14.

As clearly shown in Fig. 4, the track 6 is anchored to the base 5, by suitable anchors 50 15. The lower end of the shaft 14 bears

against the platform 9 preferably in the bearing recess therein, while the upper end thereof engages within the bearing 16 on the cross member 17.

Numerals 18 generally refers to the governor which includes the stationary collar 19 on the shaft 14 and the slideable collar 20 having the swivel ring 20a thereon. A pair of weight members 21—21 are provided, and between these weight members 21—21 and the stationary collar 19 and movable collar 20, link members 22 are provided.

The swivel ring 20a carries pintles 23 whereby the yoke 24 is swivelly connected to the said collar. This yoke 24 has an elongated arm 25 extending upwardly from the same for pivotal connection as at 26 to the bell crank 27. This bell crank 27 is located on the horizontal shaft 28 which extends at its ends beyond the outer side of the housing 70 10. The outer ends of the shaft 28 are secured to opposite sides of the frame 29, which frame has the railroad crossing gate 30 projecting longitudinally therefrom. This gate bar 30 may be equipped with a suitable signal 75 light 31 and is also provided with a prop 32.

Extending in an opposite direction from the gate bar 30 and secured to opposite ends of the shaft 28 are the bars 33 for supporting the counter-balancing weights 34.

It can now be seen that when the track circuit of the railroad is closed to energize the motor 11, the motor will serve to rotate the shaft 14. As the shaft 14 rotates, the governor 18 will contract and draw down on the arm 25, thus resulting in the lowering of the gate bar 30 (see Fig. 4).

When the gate reaches a horizontal position and is prevented by suitable stop means from lowering further, the shaft 14 will continue to rotate, but with the governor fixed against further contraction, serving nevertheless, by pressing against the yoke between the gate in a horizontal position, until the current of the railroad track block in which the motor 11 is interposed, is broken, whereupon the yoke will be released, allowing the bar 30 to rise upwardly by reason of the gravitation of the weights 34.

During this operation, the gate bar 30

moves to a position transversely of the roadway. Should a vehicle be trapped between the gate of a railroad crossing, the vehicle need only travel against the gate in its path.

5 The gate will swing with the housing, with the caster wheels 8 riding against the inclined surfaces of the track 6, until they abut the risers 7. The wheels 8 need not actually engage the risers 7, unless the gate bar is moved
10 a distance of approximately 90°. When the vehicle passes by the gate bar, the same will return back to a position transversely of the roadway by the descent of the caster wheels on the inclined surfaces of the aforementioned track 6.

15 While the foregoing specification sets forth the invention in definite terms, it is to be understood that numerous changes in the shape, size and materials may be resorted to 20 without departing from the spirit and scope of the invention as claimed hereinafter.

Having thus described my invention, what we claim as new is:—

25 1. A grade crossing gate of the character described comprising a revolvable stand, a swingable gate bar mounted on the stand, a shaft mounted within the stand, a governor on the shaft, a connection between the governor and the gate bar, and a motor for operating the shaft.

30 2. A grade crossing gate of the character described comprising a revolvable stand, a swingable gate bar mounted on the stand, a shaft mounted within the stand, a governor on the shaft, a connection between the governor and gate bar, a motor for operating the shaft, and a platform on which the motor is mounted, said platform being secured to the stand, and a wheeled support for the said platform.

35 3. A railroad gate comprising a housing, a swingable gate bar carried by the housing, a lever projecting from the gate bar, a vertical shaft within the housing, a governor operated by the shaft, a motor for operating the shaft, a swivel on the governor, and a linked connection between the arm and the said swivel on the governor.

40 In testimony whereof we affix our signatures.

OBED O. LEES.
THOMAS J. FINN.
